UNITED STATES PATENT OFFICE.

JOHN A. JONES, OF NEW YORK, N. Y.

CLOSURE FOR LIQUID CONTAINERS.

Application filed November 17, 1923. Serial No. 675,318.

To all whom it may concern:

Be it known that I, JOHN A. JONES, a citizen of the United States, and a resident of New York, in the county of New York and State of New York, have invented certain new and useful Improvements in Closures for Liquid Containers, of which the following is a specification.

This invention relates to closures for liquid containers, and especially to a device of this character for venting and directing the flow of liquid from a container and adapted for permanent attachment thereto to cover the filling opening.

15 An important object of the invention is to provide a sealing and pouring device all parts of which remain on the container at all times, and which embodies a pouring lip or spout adjacent to a pouring opening which may be provided in the closure.

Another object of the invention is the provision of a cupped closure or seal adapted to have a pouring opening formed therein, and a pouring member provided with a co-operating opening and guided in the cupped member and permanently held therein, but movable to open or close the pouring opening of the cupped seal.

30 An object of the invention is the provision of a sealing and pouring device integral with the container and adapted to have air-inlet and pouring openings made therein, said container being proof against ready refilling.

35 A further object of the invention is the provision of a closure or seal having cam portions adapted to permit wedging of a pouring member carried thereby.

Other features relate to compressible 40 means for effecting a more perfect sealing of the pouring opening; to cam means on the pouring member adapted to co-operate with guides on the interior of the cupped member to wedge the faces of the sealing 45 and pouring members together; to means for permitting introduction and positive holding of the movable member in the sealing member; and to means for preventing friction between the fixed and movable members at all times except when they are to be wedged in the closed or in the open position.

The foregoing and other features of the invention not hereinbefore referred to will be hereinafter described and claimed and

are illustrated in the accompanying drawing, in which:

Figure 1 is a top view of a sealing and associated pouring device embodying the invention and adapted for attachment to a liquid container;

Fig. 2 is a vertical section of the sealing member, taken in the line 2—2, Fig. 1;

Fig. 3 is a side view of the pouring member of Fig. 1;

Fig. 4 is a vertical section of a modified 65 form of sealing member;

Fig. 5 is a top view of a sealing and pouring device with compressible filler attached thereto;

Fig. 6 is a like view of the compressible 70 filler of Fig. 5;

Fig. 7 is a perspective view of a closure or sealing member having interior cam guides and provided with a depressed runway for a compressible insert in a co-operat- 75 ing pouring member;

Fig. 8 is a similar view of a pouring mem- 80 ber provided with cam portions for co- operation with the cam guides of the device of Fig. 7. This view also shows a com- pressible insert adapted to prevent escape 85 of liquid after the sealing member has been punctured;

Fig. 9 is a vertical section of a sealing member having interior guides for a co- 85 operating disc pouring member, and

Fig. 10 is a top view of a disc pouring member adapted for use with the sealing member of Fig. 9.

Referring to Figs. 1, 2 and 3 of the 90 drawings, 3 designates a closure or sealing member for a liquid container, it being shown herein as cupped and adapted for permanent attachment to said container, as by being soldered thereon to cover the filling opening. It is here illustrated as adapted to receive a co-operating pouring member 4, said pouring member being shown in these views as cupped and having projections or 95 studs 5 on its exterior surface adapted to co-operate with a channel or guideway 6 on the interior face of the sealing member 3. Said pourer embodies also a lip or spout 7 adapted to form a runway for the liquid while being poured. The guideway 6 is shown with cam portions such as 8 for directing the pouring member downward to wedge the contacting faces of the seal 3 100 105

and the pourer 4 together while pouring is going on, and again after pouring has been completed. It will be seen that by making the two members as shown and described 5 in Figs. 3 and 4 they may be readily combined by sliding one projection of the pouring member into the annular groove 6 and by providing a grooved portion in which the other projection may be slipped. When 10 thus assembled a half-turn in one direction serves to close a punctured opening and wedge the seal and pourer, and a half turn in the opposite direction serves to wedge the members with the vent open. 15 The vent formed for egress of the fluid is through a punctured opening 9' in the sealing member 3 and a registering opening 9 in the pouring member 4. If desired an air-inlet opening 10 may be formed in said 20 pouring member and a registering opening 10' made in the sealing member when a filled and closed container is to be vented. When the pouring and air-inlet openings have been made the liquid may be poured from the 25 container in quantities as great or as small as may be desired, and after such pouring any drip will remain in the cupped closure and tend to flow back into the container during the time the apertures in the two members are in registration. When the necessary 30 amount of liquid has been poured the container is closed by turning the pouring member 4 in its seat in the sealing member 3, this serving to carry the openings in the seal and pourer out of register and making of the pourer a shield for the openings in the seal. To wedge the faces of the two members more closely together the turning 35 movement of the pourer on its seat may be continued until the projections 5 are carried into the cam grooves 8, in which position of the parts the punctured apertures in the seal will be effectually closed. 40

In Fig. 4 I have shown a modified form of 45 closure or seal provided with interior vertical channels, such as 11, for receiving the guiding studs 5 of a pouring member as before described, and these studs may then be directed downward to the annular guideway 50 6, or the seal and pouring member may be held together and wedged in any other desired manner.

In Figs. 5 and 6 there is shown a modified form of the device before described which 55 has in addition a filler 12 of compressible material carried by the under face of the pouring member for contact with the upper face of the sealing member 3'. This compressible material may be attached to 60 the pourer in any desired manner, but is shown herein as engaged by struck-up portions of the body of the pouring member. This compressible filler is intended to provide a more perfect seal against leakage than 65 is possible when the metal surfaces contact

directly, even under pressure. When the member 4' has been turned after pouring has been effected the apertures in the members 3' and 4' pass out of register, and upon the studs 5' entering the cam portions of the 70 runway of the sealing member, the compressible pad is pressed against the face of the sealing member to effect more perfect sealing of the container. The air-inlet and liquid-pouring apertures in the compressible 75 member 12 are designated by 13 and 14 respectively.

Fig. 7 shows a sealing member 3' essentially as before described having cam guiding members 15 on its inner surface adapted 80 to co-operate with a pouring member shown in Fig. 8, the wedge cams 16 coacting with the cam 15 to wedge the two members together in pouring position or in closed position, as desired. A compressible stopper 17 85 is inserted in the member 4' and serves to close the opening 10' made in the member 3' for pouring purposes. A depressed runway pressed into the bottom of the member 3' is illustrated at 18 in which the under 90 portion of the stopper 17 may travel during that part of its movement when it is being turned from its position of compression in open position to compression in closed position in order to reduce friction. 95

Figs. 9 and 10 illustrate a modification in which the sealing member 3' is cupped and has internal guides for co-operation with a pouring member, which is here shown as a disc 22 adapted to be placed in and moved 100 within said sealing member and guided by members 23 formed during assemblage. As in other forms of my device pouring and air-inlet openings 9' and 10' are shown in said disc, and the sealing member beneath said 105 disc may be punctured in registration with these openings to provide pouring and air-inlet openings in the container. It will be obvious, however, that the air-inlet opening in this, as in other forms of closure herein, 110 may be made at any suitable point outside the closure.

In all the embodiments of my device having relatively movable sealing and pouring members these are so combined as not 115 to be subject to separation except when expressly manipulated for that purpose, and as the sealing member is an integral portion of the container there can be no misplacement of the pouring member such as 120 is often the case with cork or screw-top closing devices. Further, the movable pourer will not only remain on the container, but it can be manipulated at any time to close the vent and protect the contents 125 against entrance of foreign matter. It will be clear, also, that a container having such a seal and pourer will be proof against ready refilling.

While the pouring member is shown as 130

adapted for radial movement within the sealing member, it will be obvious that such member may be so formed and applied as to move back and forth within said sealing member to cover and uncover, and to wedge the two members in open or in closed position.

What I claim is:

1. In combination with a container having an opening, a member closing said opening and adapted to be perforated to form a pouring opening, a pouring element, and positioning means for said pouring element to force said element into sealing contact with said member in either pouring or closed position.
2. In combination with a container having an opening, a member closing said opening and adapted to be perforated to form a pouring opening, a pouring element carried in said closing member, and positioning means for said pouring element to force said element into sealing contact with said member upon rotation of said element in either direction.
3. In combination with a container having an opening, a member closing said opening and adapted to be perforated to form a pouring opening, a pouring element held and movable in said closing member, and positioning means for said pouring element to force said element into sealing contact with said member in either pouring or closed position.
4. In combination with a container having an opening, a member closing said opening and adapted to be perforated to form a pouring opening, an element carried by said member and having a pouring opening, compressible means between said member and element, and positioning means for said pouring element adapted to force said element toward said member to compress said compressible means and to effect sealing contact in any one of a number of positions.
5. In combination with a container having an opening, a member closing said opening and adapted to be perforated to form a pouring opening, a vent opening, an element carried by said member and having

a pouring opening and a vent opening therein, and positioning means for said pouring element to force said element into sealing contact with said member in either pouring or closed position.

55

6. A closure for liquid containers, comprising a sealing portion adapted to be perforated to form a pouring opening, a pouring member movably held therein, and positioning means for said pouring member to hold said member in sealing contact with said sealing portion in either pouring or closed position.

60

7. A closure for liquid containers, comprising a sealing member adapted to be perforated to form a pouring opening, a pouring member held and rotatable in said sealing member, compressible means carried by said pouring member, and positioning means for said pouring member to force it toward said compressible means to effect sealing contact with said sealing member in either open or closed position.

65

8. In combination with a container having an opening, a cupped member closing said opening and adapted to be perforated to form a pouring opening, a pouring element, and positioning means adapted to hold said element in contact with said member in any one of a number of positions.

70

9. In combination with a container having an opening, a member closing said opening and adapted to be perforated to form a pouring opening, a pouring element, and positioning means adapted to hold said element in contact with said member in any one of a number of positions.

75

10. In combination with a container having an opening, a member closing said opening and adapted to be perforated to form a pouring opening, a vent opening, a pouring element, pouring and vent openings in said element, and positioning means to hold said element in contact with said closing member to seal said member in either open or closed position.

80

Signed at New York, in the county of New York, and State of New York, this 5th day of October, A. D. 1923.

JOHN A. JONES.
